UNITED STATES PATENT OFFICE

PELLE ANDERSSON, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE

COMPRESSOR VALVE

Original application filed May 10, 1926, Serial No. 107,907. Divided and this application filed January 18, 1929. Serial No. 333,414.

The present invention relates generally to new and useful improvements in the construction of valves, and relates more specifically to improvements in valve structures especially adapted for use in connection with compressor unloading devices.

An object of the invention is to provide an improved valve structure which is simple in construction and efficient in operation. 10 Another object of the invention is to provide a new and useful disk valve which is especially applicable for unloading purposes in air and gas compressors. These and other objects of the invention will appear from the 15 following description.

The present application is a division of application Ser. No. 107,907, filed May 10, 1926, patented March 19, 1929, No. 1,706,373.

A clear conception of several embodiments 20 of the novel features and of the operation of devices embodying the invention, may be had by referring to the drawings accompanying and forming a part of this specification in which like reference characters designate 25 the same or similar parts in the various views.

Fig. 1 is a somewhat diagrammatic and part sectional side elevation of a compressor cylinder, the section being taken adjacent to one of the inlet valves.

Fig. 2 is an enlarged sectional view of one 30 of the compressor inlet valves showing the unloading mechanism associated therewith.

Fig. 3 is an enlarged sectional view of one 35 of the compressor inlet valves having a modified form of unloading mechanism associated therewith.

The compressor to which the invention has been specifically applied herein, is of the constant speed type and comprises a cylinder 40 having therein a usual form of reciprocable piston, and also having end heads 3, 4 within which are located inlet and exhaust valves communicating with the air supply and discharge conduits 36, 37 respectively. The 45 compressor piston may be reciprocated in any convenient manner, as by an electric motor, and the pressure of the compressed air delivered through the discharge conduits 37 varies according to the demand for air at the source of utilization.

The improved inlet valve structure shown in Figs. 2 and 3, comprises an annular sheet metal or plate valve 18 which is constantly urged toward an annular seat 24 formed on the seat element 20, by means of one or more springs 19 which react against a valve stop 17. The valve stop 17 is rigidly secured to the seat element 20 by means of a clamping bolt 21, and has a recess formed to receive the valve 18 when in open position, so that the discharge edge of the valve 18 is completely surrounded by an annular lip 23 when the valve is fully open.

The improved unloading device shown in Fig. 2, comprises a bridge piece or member 16 movably supported from the seat element 20 by means of parallel links 15, 25, and is disposed between the valve 18 and a positioning cam 14. The links 15, 25 are mounted to swing about upper fixed pivots and have their lower ends pivotally associated with lower pivots secured to the bridge member 16, thereby causing the contact surface of the member 16 to always assume parallel positions. The bridge member 16 carries a 75 roller 35 which is held in engagement with one of the surfaces 38, 39, 40 of the cam 14 by means of a spring 22 which reacts against the seat element 20. The cam 14 is supported upon a cam shaft 11 and has an arcuate unloading surface 38, a second arcuate bridge releasing surface 39 of shorter radius than that of the surface 38, and an intermediate surface 40 connecting the surfaces 38, 39, all of the surfaces 38, 39, 40 being adapted to 80 engage the roller 35 at certain times. The cam shaft 11 is angularly adjustable and oscillatable during operation of the compressor, by means of a rocker arm 13 and a connection 9, in a manner to be later explained.

The modified unloading device shown in Fig. 3, comprises a bridge piece or member 26 movably suspended from the cylinder head 4 and from an extension on the seat element 20, by means of an arm 27 formed integral with the member 26. The arm 27 is pivotally supported at its upper end and carries a roller 35 at its lower extremity, which cooperates with the surfaces 38, 39, 40 100

of the adjacent cam 14. The remainder of the unloading device of Fig. 3 is substantially similar to that of Fig. 2, both in structure and mode of operation, but the contact surface of the member 26 does not move to parallel positions.

The actuating mechanism for the unloading devices, comprises a regulator 5 mounted laterally adjacent to the cylinder 2 and consisting of an auxiliary cylinder having therein a vertically movable plunger 29. A pipe 28 provides a connection from the discharge conduit 37 or other pressure source, to the oil chamber within the regulator casing, and this oil chamber communicates with the plunger chamber past a needle valve 41. The plunger rod 30 is adapted to transmit motion to levers 31 which are in turn adapted to adjust the T-lever 7 about its supporting pivot 33, through a connection 32. The supporting pivot 33 of the T-lever 7 is associated with the lower swinging end of the oscillatory lever 6 the upper end of which is supported by a fixed pivot 42. The lever 6 is swingable back and forth during normal operation of the compressor, by means of a connection 34, and the upper and lower arms of the T-lever 7 are joined to the rocker arms 12, 13 by means of connections 8, 9 respectively. As previously explained, the rocker arms 12, 13 are secured to the cam shafts 10, 11 carrying the unloading cams 14.

During normal operation of the compressor, the piston is being reciprocated to alternately draw air into and discharge air from the opposite ends of the cylinder 2 through the inlet and discharge conduits 36, 37. The connection 34 is being reciprocated simultaneously with the reciprocation of the piston, thus producing oscillation of the lever 6 about the pivot 42 and causing the T-lever 7 to rock with the lever 6. The rocking motion of the T-lever 7 is transmitted through the connections 8, 9 and the arms 12, 13 to the cam shafts 10, 11 thus producing periodic rocking movement of the cams 14. When the cam 14 is in the position shown in Fig. 2 with the cam surface 38 engaging the roller 35 of the adjacent bridge member, throughout the rocking movement, the bridge member holds the inlet valve 18 in open position throughout the compression stroke and the compressor is fully unloaded. When the cam 14 is in the position shown in Fig. 3 with the cam surface 39 in engagement with the roller 35 of the bridge member, throughout the rocking movement, the bridge member does not engage the inlet valve 18 and this valve functions normally to admit air to the cylinder on the suction stroke and to prevent escape of air past the valve on the return stroke.

By proper adjustment of the position of the cams 14, unloading may obviously be effected during any desired portion of the

compression stroke. Such adjustment of the cams 14 may be automatically accomplished in accordance with variations in the discharge pressure or of any other variable operating characteristic, by means of the regulator 5. As the pressure admitted through the pipe 28 increases, the plunger 29 and rod 30 move upwardly thereby causing the cam surfaces 38 to become effective and increasing the duration of the unloading action, and vice versa.

With the construction shown in Figs. 1 and 2, the contact surface of the bridge member 16 is always advanced to parallel positions by virtue of the parallel links 15, and always has surface engagement with the valve 18 when the unloader is effective. While the construction shown in Fig. 3 does not produce such parallel positioning of the contact surface, the relatively long supporting arm 27 allows but slight angular displacement of this surface resulting in slight tilting of the valve 18.

The lip 23 surrounding the valve 18 prevents the air which returns to the inlet conduit 36 during unloading, from returning the valve to its seat 24 thereby producing highly efficient unloading. The lip 23 has special utility when applied to sheet metal valves 18 used in connection with compressor unloading devices, as it prevents the air which is returned to the inlet conduit, from forcing the peripheral edges of the valve toward its seat 24, and thereby undesirably restricting the free delivery of air from within the cylinder. When unloading is taking place, the annular plate valve 18 is positioned entirely within the annular recess of the valve stop 17, and the air being delivered from the cylinder does not come in contact with the side of the valve which faces the cylinder, excepting when the valve 18 is in closed position. The annular sheet metal or plate valves 18 are of simple construction and have proven highly efficient in operation.

It should be understood that it is not desired to limit the invention claimed to the exact details of construction shown and described, for obvious modifications may occur to persons skilled in the art.

It is claimed and desired to secure by Letters Patent:

1. An unloading device for compressors comprising in combination, a valve seat element adapted to be inserted in a compressor, a valve therein actuated during operation of the compressor, a stop for limiting the opening movement of said valve secured to said seat element, said stop being provided with an annular lip for closely surrounding a periphery of said valve when in full open position and means for holding said valve in full open position during unloading of the compressor.
2. In a one-way inlet valve structure for

compressors, a valve seat element adapted to be inserted in a compressor, an annular sheet metal valve, a stop for limiting the opening movement of said valve secured to said seat element, said stop having an annular lip completely surrounding the periphery of said valve when fully open, means for constantly urging said valve away from said stop, and means for holding said valve within said lip during unloading of the compressor.

3. In a one-way inlet valve structure for compressors, a valve seat element adapted to be inserted in a compressor, an annular sheet metal valve, spring means for constantly urging said valve toward closed position, a stop for limiting the opening movement of said valve secured to said seat element, said stop having an annular projection surrounding the periphery of said valve when fully open, and means for holding said valve within said projection during unloading of the compressor.

4. In a one-way inlet valve structure for compressors, a valve seat element adapted to be inserted in a compressor, an annular sheet metal valve, a stop for limiting the opening movement of said valve secured to said seat element, said stop having a recess forming a lip entirely surrounding the periphery of said valve when open, and a bridge member for holding said valve within said stop recess during unloading of the compressor.

5. In a one-way inlet valve structure for compressors, a valve seat element adapted to be inserted in a compressor, a sheet metal valve, a stop for limiting the opening movement of said valve secured to said seat element, said stop having a recess therein forming a projection surrounding the periphery of said valve when open, and means for holding said valve within said recess, to permit free escape of air from the compressor around said projection during unloading of the compressor.

45 6. In a one-way inlet valve structure for compressors, a valve seat element adapted to be inserted in a compressor, an annular plate valve, a stop for said valve secured to said seat element, said stop having an annular recess adjacent to said valve, and means for holding said valve entirely within said recess during unloading of the compressor.

7. In a one-way inlet valve structure for compressors, a valve seat element adapted to be inserted in a compressor, an annular plate valve, a stop for said valve secured to said seat element, for limiting the opening movement of said valve, said stop having a recess adjacent to said valve, and means for holding said valve entirely within said recess when at a maximum distance from said seat element.

In testimony whereof, the signature of the inventor is affixed hereto.

65 PELLE ANDERSSON.
